UNITED STATES PATENT OFFICE.

TIMOTHY E. WEST, OF OAKLAND, CALIFORNIA.

PARCEL-POST AND EXPRESS CHART.

1,422,245.

Specification of Letters Patent.

Patented July 11, 1922.

Application filed September 19, 1918. Serial No. 254,815.

To all whom it may concern:

Be it known that I, TIMOTHY E. WEST, citizen of the United States, residing at Oakland, in the county of Alameda and 5 State of California, have invented certain new and useful Improvements in Parcel-Post and Express Charts, of which the following is a specification.

My invention is a computing system particularly adapted for quickly determining 10 both express and parcel post rates between express and parcel post stations.

In this specification and the annexed drawing, I disclose my invention in the 15 form which I consider the best, but I do not limit my invention to such form because it may be embodied in other forms and it is to be understood that in and by the claims following the description herein I intend 20 to cover my invention in whatever form it may be embodied.

Referring to the drawings:

Figure 1 is a view of plate No. 1 used in 25 my computing system.

Figure 2 is a view of plate No. 2 used in my computing system.

Figure 3 is a view of plate No. 3 of my 30 computing system.

Figure 4 is a view of plate No. 4 of my computing system.

Figure 5 is a view of plate 5 of the system.

The parcel post system has divided the United States into units of area thirty minutes square, identical with a quarter of the 35 area formed by the intersecting parallels of latitude and meridians of longitude, these quadrangles are called parcel-post units, and these units form the basis of eight parcel post zones.

40 The zone location of any city from a known point is determined by referring to a parcel post map, or official zone key sheet, and noting the location of the quadrangle or unit, noting the distance and the relative 45 location in regard to zone circle, zone circles radiate from the center of units and all units included in a zone circle radiating from the center of a unit in which is located a town or city indicate the particular zone 50 location of said unit from said city.

In order to regulate express rates or charges, the Interstate Commerce Commission has divided the United States into quadrangles the division being according to 55 meridians and parallels, and these quadrangles represent the area contained inside

of sixty minutes of latitude and longitude. These quadrangles are called express blocks.

The express charges are determined according to distances between express blocks, 60 but rates are not always uniform according to distances, on account of express zones and intrastate regulations governed by State commissions. Scale numbers is the term used in referring to express rates and scale 65 numbers are numbered from 0 to 294. Under scale numbers the graduated rates are classified.

For example, the parcel post zone location of Chicago, Illinois, from Washington, 70 D. C., is 4 and is found by referring to a parcel post map of Washington, D. C. or it can also be determined by referring to a Chicago parcel post map, and noting the zone location of Washington unit which is 75 1071. Knowing now that the zone location between Chicago and Washington, D. C., is fourth zone, and then referring to fourth zone parcel post rates, a 20 pound shipment would be 83¢.

80 Now, by referring to a Washington, D. C., express guide or a Chicago express guide, we note that the scale to rates between these two points is 35 and by referring to the rates listed under scale 35 we find that a 20 pound shipment between these two cities is 65¢.

The scale number between Chicago and Washington, D. C., is the scale to rates applying between express block 838 and 1148 and this scale to rates applies between any 90 town located in block 838 to any town located in block 1148.

The above method used by shippers all over the United States to determine the comparison between parcel post and express 95 charges means that they have to consult two books or guides, which procedure consumes a great deal of time, namely, postal guides and express guides.

My invention is arranged to get the above 100 results in a simpler method, namely the arrangement of figures so arranged that a shipper can instantly know the zone location, and the express scale number at a glance. My invention consists of a number 105 which I call a key number for convenience, arranged so that the first figure at the left will denote the parcel post zone number and the balance of the number representing the express scale number. For example: The 110 zone number between Washington, D. C. and Chicago, Ill., as explained above, is 4 and

the express scale number is 35; therefore key number to rates between Washington, D. C. and Chicago, Ill., would be 435. Take for example another illustration: Denver, Colo., 5 is located in parcel post unit 3819 which is located in express block 1021 and we wish to know the rates from Denver, Colo., to the following towns, namely: Obar, New Mexico; Logan, New Mexico; Mosquero, New Mexico and Tucumcari, New Mexico.

10 Denver, Colo., express block 1021, parcel post unit 3819 to—

15 Cities.	Express block.	Parcel post unit.	Zone.	Scale.	Key number.
Obar, N. M.	1422	3677	3	35	335
Logan, N. M.	1422	3678	4	35	435
Mosquero, N. M.	1422	3727	3	35	335
Tucumcari, N. M.	1422	3728	3	35	335

20 The express scale to rates from Denver, Colo., block 1021 to express block 1422 which is the block that the above cities are located in is 35. There are four parcel post units in block 1422 as follows: 3677, 3678, 3727, 3728. One of these units 3678 is in fourth parcel post zone from Denver 3819, while the other three units are in the third parcel post zone from Denver. This being 25 the case, the key number to rates from Denver, Colo., to the following named cities 30 will be as follows:

Denver, Colo., to Obar, New Mexico, key number 335 indicating 3rd parcel post zone; 35 express scale 35.

Denver, Colo., to Logan, New Mexico, key number 435 indicating 4th parcel post zone; express scale 35.

Denver, Colo., to Mosquero, New Mexico, 40 key number 335 indicating 3rd parcel post zone; express scale 35.

Denver, Colo., to Tucumcari, New Mexico, key number 335 indicating 3rd parcel post zone; express scale 35.

45 The rates under an express scale number are subject to change by either raising or lowering said rates, and are subject to decisions of the Interstate Commerce Commission on interstate rates, and subject to 50 change on intrastate rates by State railroad commissions of the different States in the Union. In other words, the rate for a one pound shipment from San Francisco, Cal., to some town in California under scale 35 would be 23¢, said rate being regulated by 55 the California State Railroad Commission, while the rate from San Francisco to some town located in some other State, other than California, taking the same scale 35 could 60 be 27¢. This last rate being regulated by Interstate Commerce Commission at Washington, D. C. These rates vary mostly on weights from one to one hundred pounds, the hundred pounds generally remaining 65 the same. In order to simplify this differ-

ence, I will take as an illustration a town in the State of California. The scale to rates on express from San Francisco, Cal., to Ventura, Cal., is 35 under California State Railroad Commission decisions the charge for 70 a one pound shipment under scale 35 is 23¢, as compared against a charge of 27¢ on a one pound shipment from San Francisco to towns outside of California under same scale 35. 75

Since there is no 9th zone in the postal system, I will in order to distinguish the differences between rates under the same scale numbers on interstate and intrastate charges, add the figure 9 to left of a key 80 number to denote intrastate charges. This intrastate key number would then show as follows: key number 9335 would indicate that the charges under this number indicates shipment entirely within the State and 85 rates are lower than rates regulated by Interstate Commerce Commission and that a difference in rates was evident. The next figure 3 which follows 9 will indicate 3rd parcel post zone, and the remaining figure 90 35 indicates the express scale number as shown in plate 4.

The function of plate No. 1 is to determine the key numbers which indicate the 95 parcel post zones and the express scale numbers, of the cities and towns of the State of New Mexico with relation to the cities of Los Angeles and San Francisco, California, and to determine the parcel post unit numbers of said towns and cities of New Mexico. 100

In plate No. 1 there are four columns on the left half of the plate, respectively indicated at the top "Parcel post unit"; "Post office and express stations"; "Key to rates from Los Angeles" and "Key to rates from 105 San Francisco." In the column designated "Post offices and express stations" are arranged alphabetically a list of the post offices and express stations in the State of New Mexico. In the column designated 110 "Parcel post unit" are arranged, respectively opposite said post offices and express stations, the numbers of the "Parcel post units" in which said post offices and express stations are located. In the column designated 115 "Key to rates from Los Angeles" are arranged, respectively opposite said post offices and express stations, the key numbers to the parcel post and express rates from Los Angeles, Calif. to said post offices and express 120 stations in New Mexico. In the column designated "Key to rates from San Francisco" are arranged, respectively opposite said post offices and express stations, the key numbers to the parcel post and express rates 125 from San Francisco, California to said post offices and express stations in New Mexico. On the right half of plate No. 1 the above described columns and indicia contained therein are continued. 130

Certain characters are placed after the cities and towns to designate certain things. The character * indicates that there is a money order post office at the station. A 5 Western Union Telegraph office is designated ①. Postal Telegraph office is designated ②. Railroads connecting with the station are indicated by numbers which are listed in a separate table. Express companies 10 are designated by letters.

The function of plate No. 2 is to determine the key numbers to the parcel post and express rates between several leading cities of the United States, namely: Boston, Chicago, 15 Cincinnati, Cleveland, Denver, Detroit, New York, Philadelphia, Portland, Ore., Salt Lake and Seattle; and the parcel post units of the State of New Mexico in which units are located the post offices and express 20 stations of New Mexico.

In plate No. 2 there are twelve columns respectively designated at the top: "Parcel post units; "Boston"; "Chicago"; "Cincinnati"; "Cleveland"; "Denver"; "Detroit"; 25 "New York"; "Philadelphia"; "Portland, Ore."; "Salt Lake"; "Seattle".

In the parcel post units column are arranged, in increasing numerical order from the top to the bottom of the column, the parcel post unit numbers of the State of New Mexico. In the city columns are respectively arranged opposite the parcel post unit numbers, the key numbers to the parcel post and express rates between the cities designating said columns and the parcel post 35 units of New Mexico designated by the numbers in the parcel post unit column.

The function of plate No. 3 is to determine by the key numbers found in plates No. 1 40 and 2 the parcel post and the express rates between Los Angeles and San Francisco and the post offices and express stations of New Mexico indicated in plate No. 1, and the parcel post and express rates between the cities 45 of Boston, Chicago, Cincinnati, Cleveland, Denver, Detroit, New York, Philadelphia, Portland, Ore. Salt Lake and Seattle and the parcel post units of New Mexico indicated in plate No. 2.

50 In plate No. 3 there are thirteen columns. The first column is designated "pounds." The next eleven columns are express rate columns. These columns are designated respectively at the top by parcel post and express rate key numbers "577" to "587" inclusive from left to right. Said columns are also each designated "Express" to indicate express rates. Each of said columns is divided into two columns designated respectively "1st class" and "2nd class" to indicate 55 1st class and 2nd class express rates. The last column to the right is the parcel post rate column designated "parcel post zone 5" "Fourth class mail rates." In the pounds 60 column are arranged from top to bottom the

numbers "1 to 100" inclusive indicating pounds. In each express rate column are arranged, in the 1st and 2nd rate columns, opposite the "pounds" numbers, the first and second class express rates according to 70 pounds between Los Angeles and San Francisco and the express stations of New Mexico as indicated in plate No. 1, and the express rates between eleven cities and parcel post units of New Mexico according to 75 pounds as indicated in plate No. 2. In the last column are arranged opposite the "pounds" numbers the parcel post rates according to pounds between Los Angeles and San Francisco and the post offices of New 80 Mexico, as indicated in plate No. 1, and the parcel post rates according to pounds between the eleven cities and the parcel post units as indicated in plate No. 2.

The function of plate No. 4 is to determine, by the key numbers found in plate 85 No. 1, intrastate rates between points in New Mexico. The arrangement of plate No. 4 is the same as that of plate No. 1 with the exception of the intrastate key number 9 at 90 the left of each parcel post and express key number.

Plate 5 is a parcel post schedule of rates classified under the zone system, now in use by the postal system.

95

Parcel post and express rates are determined as follows:

If it is desired to find these rates for 10 pounds from Los Angeles, California to Albuquerque, New Mexico, plate No. 1 is 100 first referred to. In the column designated "Post offices and express stations" is found the city of Albuquerque. This city has a post office as indicated by the character *; a railroad is indicated by the numeral 9 which according to my system is the Atchison, 105 Topeka & Santa Fe; a Western Union Telegraph office indicated by the character 1; a Postal Telegraph indicated 2; and a Wells Fargo Express office indicated WF. To the 110 right of the city of Albuquerque is found in the column designated "Key to rates from Los Angeles" the key number of said city which is 585. Plate No. 3 is now consulted. From Los Angeles, Albuquerque is found to 115 be in parcel post zone 5 according to the column at the right of said plate and the parcel post rate between these two cities is found in said column opposite the number 10 120 in the pounds column to the left of the plate which is 62¢.

The first and second class express rates from Los Angeles to Albuquerque are found in the column indicated by key number 585 in the 1st class and 2nd class columns of 125 said key number column opposite the number 10 in the pounds column to the left; which rates are respectively 70¢ and 53¢. Thus both parcel post and express rates are both readily found. By a comparison of 130

said rates: it is found that the cheapest rate between Los Angeles and Albuquerque for 10 pounds is the second class express rate of 53¢.

5 If it is desired to find the parcel post and express rates for 15 pounds between Chicago and Cameron, New Mexico, plates Nos. 1, 2 and 3 are consulted in order. The number of the parcel post unit in which Cameron, 10 New Mexico, is located is found in plate No. 1 opposite Cameron in parcel post unit column, which unit number is 3679. Plate No. 2 is then consulted. The key number to parcel post and express rates is found opposite 15 parcel post unit 3679 in the Chicago column which number is 583. By consulting plate No. 3 as before pointed out the parcel post rate between Cameron, New Mexico, and Chicago for 15 pounds is 92¢ and the 1st 20 and 2nd class express rates between said cities is 91¢ and 69¢ respectively.

In computing intrastate rates plates 1 and 4 are used in the same manner as plates 1 and 3. Plate 1, however, instead of having 25 points outside of the State at the head of the key columns will have the points within the State from which the rates are computed.

At many points in a State there are no express stations but there are post offices. 30 In the key columns of plate 1 the parcel post zone numbers are indicated after such points. The rates to these points are computed with said zone numbers in plate 5 which is the usual parcel post schedule.

35 I have disclosed only one unit of my computing system but as many units may be used as desirable. The system as disclosed applies to interstate rates only between Los Angeles, San Francisco, Boston, Chicago, 40 Cincinnati, Cleveland, Denver, Detroit, New York, Philadelphia, Portland, Ore., Salt Lake and Seattle and post offices and stations in New Mexico; and to intrastate rates between points in New Mexico indicated in plate 1. The plates shown in the drawings are not complete in themselves; they illustrate only a portion of the plates which is all that is necessary to illustrate the principle of the invention. In a system for the entire 45 United States there would be plates applicable to all the States in the Union.

While the system is particularly applicable to parcel post and express rates, the invention is not restricted to such application.

50 Having described my invention, I claim as new and desire to secure by Letters Patent:

1. In a chart, a plate, means on said plate 55 for determining a desired unit number; a second plate, means on said second plate for determining a key number by the unit number determined in said first plate; a third plate, and means on said third plate for determining a plurality of results with the

use of the key number determined in said second plate.

2. In a chart, a plate, means on said plate for determining the unit number of a certain point, a second plate, means on said second plate for determining by said unit number the key number to parcel post and express rates between said point and another point, a third plate, and means on said third plate for determining by said key number the parcel post and the express rates between said two points. 70 75

3. In a chart, a plate on which are two columns, a list of points in one of said columns, unit numbers in said second column respectively opposite said points, a second plate on which are a plurality of columns, unit numbers in one of said columns corresponding respectively to the unit numbers in another column of said second plate corresponding respectively to said unit numbers, a third plate, a plurality of columns on said third plate headed respectively by the key numbers of said second plate, numbers in said key columns indicative respectively of a relation between said unit numbers and a desired point indicated at the head of the key number column of said second plate, another column on said third plate, a number in said column indicative of another relation between said unit numbers and said desired point. 80 85 90

4. A chart including a plate on which are two columns, a list of post offices and stations in one of said columns, unit numbers in said other column indicating respectively the parcel post units in which said post offices and stations are located; a second plate, a plurality of columns on said second plate, said unit numbers being arranged 100 in one of said columns, key numbers in another column indicative of parcel post rates and railroad rates respectively between said units and a desired point indicated in said key number column; a third plate, a plurality of columns on said third plate headed by said key numbers, railroad rates in said key number columns respectively between the stations, indicated by the unit and key numbers, and said desired point, another column on said second plate, and parcel post rates in said latter column respectively between said post offices, indicated by said key and unit numbers, and said desired point. 105 110 115

5. A chart including a plate on which are three columns, a list of post offices and stations in one of said columns, unit numbers in another column indicating respectively the parcel post units in which said post offices and stations are located, key numbers in another column indicative of parcel post rates and railroad rates respectively between said post offices and stations and a desired point indicated at the head of said column, 120 125 130

a second plate, a plurality of columns on said second plate, said unit numbers being arranged in one of said columns, key numbers in another column indicative of parcel post rates and railroad rates respectively between said units and a desired point indicated in said key number column, a third plate, a plurality of columns on said third plate headed by said key numbers, railroad rates in said key number columns respectively between the stations, indicated by the unit and key numbers, and said desired points, another column on said second plate, and parcel post rates in said latter column respectively between said post offices, indicated by said key and unit numbers, and said desired points.

6. A chart including a plate on which are a list of points, key numbers on said plate, respectively opposite said points, a point at the head of said key column, a second plate on which are placed said key numbers, and resultants classified under said key numbers on said second plate, said resultants determining a relation between the respective points of said list and the point at the head of said key column.

7. A system for computing parcel post rates including a plate on which are a list of parcel post stations, parcel post zone numbers arranged respectively opposite said parcel post stations, a parcel post station at the head of said zone numbers located respectively with relation to said stations in the zones opposite said stations, and a parcel post table for computing the zone rates in said plate.

8. A chart including a plate, on which are arranged a list of shipping points in a State with relation to another shipping point in the same State, key numbers to transportation rates between said shipping point and said other point, another plate for computing the intrastate rates between the respective points in said list and said other point with the use of said key numbers arranged on said second plate, and an additional number associated with said key numbers in said second plate to indicate intrastate rates.

In testimony whereof I affix my signature.

TIMOTHY E. WEST.
